UNITED STATES PATENT OFFICE.

ALBERT H. LEWIS, OF NEW COMERSTOWN, OHIO, ASSIGNEE OF ONE-THIRD TO CHARLES R. STARKER AND ONE-THIRD TO CHARLES C. STARKER, BOTH OF NEW COMERS- TOWN, OHIO.

COLLAPSIBLE CORE-BAR.

1,078,446.

Specification of Letters Patent. Patented Nov. 11, 1913.

Application filed June 3, 1913. Serial No. 771,469.

To all whom it may concern:

Be it known that I, ALBERT H. LEWIS, a citizen of the United States, residing at New Comerstown, in the county of Tuscarawas and State of Ohio, have invented new and useful Improvements in Collapsible Core-Bars, of which the following is a specification.

My present invention has to do with collapsible core bars, such as are used in metal founding; and it contemplates the provision of a sectional and collapsible core bar, embodying peculiar and advantageous means for detachably securing the sections against movement with respect to each other, and for releasing the sections at the proper time for such movement, so as to facilitate the withdrawal of the core bar.

With the foregoing in mind, the invention in all of its details will be fully understood from the following description and claims when the same are read in connection with the drawings, accompanying and forming part of this specification, in which:

Figure 1 is a view, partly in elevation and partly in section, showing my novel core bar or print with the body sections locked for use. Fig. 2 is a similar view showing the core bar or print in a collapsed state. Fig. 3 is an enlarged detail section illustrative of the resilient latches and the parts adjacent thereto. Figs. 4 and 5 are sections taken on the lines 4-4 and 5-5, respectively, of Fig. 1.

Similar letters designate corresponding parts in all of the views of the drawings, referring to which:

A A are the downwardly-tapered metallic sections, and B B are the upwardly-tapered metallic sections, comprised in the cylindrical body of the core bar; the sections A being arranged opposite each other, as are also the sections B, and the sections B being interposed between the sections A and vice versa.

C is a central stem arranged within the cylindrical body, and having an aperture a adjacent its upper end, and equipped with collars b b'; the said collars b b' being fixed to the stem by set screws b², or other means compatible with the purpose of my invention.

D is a vertically-movable sleeve that rests

on the lower collar b, and surrounds the stem C and has a large base flange c, and an upper and comparatively small flange d, and surrounding and movable vertically on said sleeve D is a collar E to which are pivoted the inner ends of links F, the outer ends of said links being pivoted to ribs e on the inner sides of the sections A.

Pivoted to the large base flange c of the sleeve D are links e', and these links e' are pivoted at their outer ends to lugs e² on the inner sides of the sections B.

Fixed by a set screw f or other means to the stem C is a collar F², and pivoted to the said collar F² are vertically swinging arms G, which are designed to bear at their outer ends against the inner sides of the sections A.

At H on the stem C is a vertically movable sleeve having a base flange g and an upper comparatively small flange h. Pivoted to the said base flange g, which rests on the collar b', are the inner ends of vertically swinging links h², the outer ends of the said links h² being pivotally connected to lugs h³ on the inner sides of the sections B. In the sleeve H and extending between the flanges g and h are diametrically opposite slots i, and formed in the shaft or stem C is a diametrical slot i², which is registered with the said slots i. Arranged in the said slots i and i² and fixedly connected at their lower ends to the stem C are resilient latches I. The said latches are provided with intermediate outwardly-projecting and rounded portions k, and are also provided with beveled heads or upper ends l.

Surrounding the sleeve H and the latches I and movable vertically between the flanges g and h of the sleeve, is a collar J, and connecting the said collar with lugs e⁴ on the inner sides of the sections A are vertically swinging links K.

The collar J is provided with diametrically opposite arms J², and fixed with respect to and rising from the said arms J² are upright rods J³ having heads at their upper ends. Movable vertically on the said rods between the arms J² and the heads of the rods are bars J⁴, and to each of the said bars J⁴ is connected a coupling J⁵.

Pivotedly connected at their lower ends to the arms G are vertical rods M, the upper

end portions of which are bifurcated, and are pivotally connected to the ends of the bars J^4 .

Pivotally connected at their ends to the 5 collar E and the collar J are rods P.

The couplings J^6 are designed to be engaged by the hook-shaped arms of vertically swinging levers Q, the other arms of said levers being comparatively heavy. The 10 levers Q are fulcrumed on links at the lower ends of chains R, and the said chains R are connected, in turn, to a ring S. This ring S is designed to be connected to a cable (not shown), for use in lowering the core bar 15 and in raising the same from a flask. Also connected to the ring S is a chain T which is connected in turn to a clevis U, a portion of which is disposed in the aperture a of the stem C. A bar V disposed in comparatively 20 long links w of the chains R, is extended through a link of the chain T, and is designed to be moved vertically by the said chain T, and also by the chains R, as hereinafter described. It will be noticed, however, at this point that because of the 25 disposition of the bar V in the long links w, the chains R can be moved upwardly to a limited extent independently of the bar V and the chain T.

30 In the practical use of my improvements, the core bar or print is placed in a flask with the aid of the chain T connected with the stem C, and at any suitable time precedent to the withdrawal of the bar or print, 35 the hooks of the levers Q are engaged with the couplings J^6 .

When it is desired to remove or withdraw the core bar or print, upward pull is exerted on the ring S. The said upward pull 40 will first raise the couplings J^6 and thereby draw the arms or latches G upwardly and inwardly. Subsequently to the said movement of the arms or latches G, the continued upward pull on the couplings J^6 will, by 45 reason of the bars J^4 acting against the heads of the rods J^8 , raise the collars E and J so as to raise and draw inwardly the body sections A. The upward movement of the collar J will press the latches I inwardly so 50 as to enable the sleeve H to clear the heads of said latches, and then the collars E and J acting against the upper flanges of the sleeves D and H, respectively, will move the said sleeves D and H upwardly, and release 55 all parts so as to enable the body sections B to move downwardly and contribute to the reduction of the core bar or print in diameter so that the same can be readily withdrawn. Continued upward pull on the 60 ring S will then raise the device as a unit.

I have entered into a detailed description

of the construction and relative arrangement of the parts embraced in the present and preferred embodiment of my invention in order to impart a full, clear, and exact 65 understanding of the said embodiment. I do not desire, however, to be understood as confining myself to the said specific construction and relative arrangement of parts, as, in the future practice of the invention, 70 such changes or modifications may be made as fairly fall within the scope of my appended claims.

Having described my invention, what I 75 claim and desire to secure by Letters-Pat- ent, is:

1. The combination with a body having opposite downwardly-tapered sections and opposite upwardly-tapered sections, one pair of sections being movable with respect 80 to the other, of a stem disposed within the group of body sections, movable latches carried by said stem and arranged to hold one pair of body sections against movement, collars movable on the stem in the direction of 85 the length thereof and connected with said pair of sections, means for moving the latches and the collars in the order named, and means connecting the other pair of body sections with the stem. 90

2. The combination with a body comprising opposite downwardly-tapered sections and opposite upwardly tapered sections alternating with the downwardly tapered sections, one pair of sections being movable 95 with respect to the other, of a stem disposed within the group of sections, sleeves movable endwise on the stem and normally resting on supports carried thereby, said sleeves having lower and upper flanges, and the 100 upper sleeve having diametrically opposite slots registered with a diametrical slot in the stem, links connecting the lower flanges of the sleeves with opposite body sections, swinging latches connected with the stem 105 and bearing against the inner sides of the other body sections, collars movable on the sleeves, connections between the collars, devices carried by and movable vertically, independently of the upper collar and connected with the latches, resilient latches fixed to the stem and movably arranged in the slots of the stem and upper sleeve and having heads disposed above the upper sleeve. 115

In testimony whereof I have hereunto set my hand in presence of two subscribing witnesses.

ALBERT H. LEWIS.
